UNITED STATES PATENT OFFICE.

JOHANN FRIEDRICH SIEMS, OF COLUMBUS, NEBRASKA.

HEN-PROTECTOR.

SPECIFICATION forming part of Letters Patent No. 712,339, dated October 28, 1902.

Application filed July 31, 1901. Serial No. 70,423. (No model.)

To all whom it may concern:

Be it known that I, JOHANN FRIEDRICH SIEMS, a citizen of the United States, residing at Columbus, in the county of Platte and State 5 of Nebraska, have invented certain new and useful Improvements in Divisional Breeding-Hen Protectors; and I do hereby declare the following to be a full, clear, and exact description of the invention, such as will enable 10 others skilled in the art to which it appertains to make and use the same.

My invention relates to what I shall for convenience term a "hen-protector," and it consists of certain novel features of combination 15 and construction of parts, the preferred materialization whereof will be fully described in the following specification and illustrated in the accompanying drawings, which form a part of this application.

20 The prime object of my invention is to provide an appliance which will be found very desirable, cheap, and efficient, that will reliably perform its office of sheltering and protecting any desired number of sitting hens 25 or other fowl and insure that they will be guarded against being disturbed during the period of incubation.

A further object of my invention is to disclose certain plans of construction which may 30 be adopted that will materially lessen the cost of production of my improved natural-hen incubating appliance.

Other objects and advantages will be clearly apparent from the following specification, reference being had to the accompanying drawings, in which—

Figure 1 is a perspective view of one form of my invention complete, showing a portion of the covering thereof removed. Fig. 2 is a 40 transverse section of Fig. 1. Fig. 3 is a longitudinal section of Fig. 1 on line *xx*. Fig. 4 is a detail view illustrating the preferred manner of cutting or preparing the partition-boards and end sections for that form of incubator illustrated in Fig. 6. Fig. 5 illustrates a modified form of construction from that presented in Fig. 1, wherein it will be observed that the capacity of the incubator is doubled by locating a series of nests in 45 each side thereof. Fig. 6 is a perspective detail view showing another form of construction from that presented in Fig. 1, illustrat-

ing another method which may be adopted for opening and closing the series of doors. Fig. 7 is a detail view showing two of the 55 doors illustrated in Fig. 6 disposed in a closed position, while Fig. 8 is a similar view showing one of the doors opened or elevated.

In order to readily refer to the various details of my invention and the coöperating accessories, said parts will be designated by numerals, the same numeral applying to a similar part throughout the several views.

While in many instances artificial means may be adopted to complete the process of 65 incubation, as by the use of any of the well-known incubating-machines, I prefer under most circumstances to utilize the mother hen for this purpose, and it therefore becomes desirable and important that the hen or other 70 fowl shall be safely housed and fully protected against being disturbed by surrounding adverse conditions; and with this object in view it may be briefly stated that my invention consists in a convenient form of appliance whereby the hen may be provided with an individual compartment containing 75 a nest and also connected with a suitable passage or run, which latter may be utilized for the purpose of exercise and to gain access to 80 vessels containing food and drink.

In materializing my invention I provide a suitable housing comprising the end sections 1 and the side walls 2, properly secured together in any preferred way, it being understood that the area and depth of the compartment to be provided may be of any desired size or capacity. It will be further obvious that my improved natural-hen incubator may be made so as to have what may be 90 termed a "single capacity," as illustrated in Fig. 1, or such capacity may be doubled, as illustrated in Fig. 5.

In Fig. 1 it will be observed that I have provided a series of box-like compartments 95 arranged along one side of the incubator, said compartments being separated from the interior by means of the partition-walls 3, each of said walls being cut away, as indicated by the numeral 4, to provide an opening through 100 which the hen may pass into the passage-way, extending transversely across the incubator and separated from each other by a series of partition-walls 5, extending entirely across

from wall to wall 2, all of said parts being properly secured in any preferred way. Each of the box-like compartments formed by the partition-walls 3 and 5 and the adjacent exterior wall is designed as a receptacle for the hen or other fowl, a suitable nest being provided within said compartment adapted to receive the eggs to be subjected to the incubating process. Each of the nest-compartments is provided with a suitable individual door 6, preferably connected to the wall 2 by a hinge or hinges 7 in order that said doors may be readily opened outward, a proper inclination or pitch being given to each of said doors by means of the inclined or beveled section 8, nailed to a contiguous part of the end walls 1 and the partitions 5, as will be obvious.

By the arrangement just described it will be observed that the partition-walls 5 will insure that suitable runs or passage-ways will be provided to coöperate with each individual nest, and since a passage-way for the hen is formed in the partition-walls 3 it is clear that the hen may freely pass from the nest into the passage-way, which is preferably left open for the admission of light and air and at the same time properly inclosed to prevent the escape of the fowl. I therefore prefer to provide a covering of wire, as indicated by the numeral 9. It will be understood that suitable vessels for food and drink may be provided, as indicated by the numerals 10 and 11 in Fig. 1, while the outer ends of the runs or passage-ways are rendered conveniently accessible by suitable doors 12, hinged to a strip 13, as indicated by the numeral 14.

It becomes desirable to provide a convenient form of door for each of the openings in the partitions 3, and with this object in view I provide a plurality of door-sections 15, each connected to or forming an integral part of the controlling-shaft 16, the said doors being located upon said shaft at such a point that each of the doors may be brought simultaneously in position by a proper movement of the shaft 16, so that all of the openings will be closed, while said openings may all be readily opened by a reverse movement of the shaft 16.

In order to provide efficient and convenient means for longitudinally moving the shaft 16, I adopt the controlling-lever 17, pivotally connected to the bracket 18, attached to a convenient point upon the end section 1 and also connected pivotally to the outer end of the shaft 16, as indicated by the numeral 19, a suitable slot or opening 20 being formed in the lever in order to compensate for the relative position of the shaft and lever during the operation of said parts.

I prefer to so form the individual door-sections 15 that they will not completely cover or inclose the openings formed in the partitions 3, as better results will follow when the doors 15 are of less extent than said openings,

thereby insuring that proper ventilation and light will be afforded the occupant of the nest-compartment.

In order to further facilitate a free circulation of air, each of the door-sections 15 may be provided with a plurality of apertures 21, it being understood that said door-sections may be an integral part of the shaft 16, as by forming all of said parts from a single board properly cut away, or said doors may be separately formed and connected to the shaft 16, as by nailing or otherwise securing the same thereto, and if this last method is adopted better results would probably follow if the grain of the wood forming the doors extended at right angles to the grain of the wood forming the shaft 16, as is obvious. It is also clear that the doors may be formed of tin or other suitable material, if desired. The shaft 16, with its accompanying doors, is securely mounted in position by directing the doors carried by said shaft downward in proper position to lie parallel and in contact with the partitions 3, one side of the shaft being thus disposed against the upwardly-extending ends of the partitions 3, while the other side of said shaft contacts with the board section 22, which extends entirely across the top of my incubator from end to end and may be secured in place, as by nailing or otherwise securing the same to the contiguous part of the end sections and partitions 5, it being understood that a suitable space shall be left between said board section 22 and the partitions 3 to accommodate and permit the free movement of the shaft 16 with its accompanying door-sections. It is therefore obvious that the operator may very readily open and as quickly close all of the openings in the partitions 3 by a simple movement of the controlling-lever 17, provided for this purpose. It becomes desirable at certain times during the day to permit the hens or other fowls inclosed to leave their nests for exercise and food, and this may be readily accomplished by opening all of the doors at certain periods and again closing them at the proper hour.

In some instances it may be desirable to provide a bottom for the incubator, though ordinarily it may be placed directly upon the ground. It is thought that the best form of bottom may be made of galvanized wire-netting, as this will exclude moles or other burrowing enemies of the fowls and at the same time guard against undue deterioration.

In Fig. 5 I have illustrated the same form of natural-hen incubator as shown in Fig. 1, excepting that the incubator illustrated in Fig. 5 has a double capacity, inasmuch as it will be observed that each side of the framework comprising the body portion of my incubator is provided with a plurality of compartments, as indicated by the numeral 23, the partition-walls 3 and 5 being substantially the same as those illustrated in Fig. 1, except, of course, that the partitions 5 shall be of greater length. In practice it is thought that

the length of each of the runs or passage-ways connecting with the nests shall be about eight feet, more or less. By this arrangement the passage-way or run between the nests may be 5 used in common by the two hens occupying the nests at the ends thereof, or one of the hens may be permitted to use the passage-way for certain hours of the day by properly manipulating the door-sections by means of 10 the controlling-shafts 16, said doors and shafts being substantially the same as described in the foregoing specification. In like manner each of the series of nests is provided with an individual door-section 6, as clearly set forth, 15 it being understood that a central series of doors 24 are provided and properly hinged to the anchoring-section 25, as clearly shown in Fig. 5. The shaft-sections are held against inward movement by means of the strips 26, 20 nailed or otherwise secured to a contiguous part of the partitions 5. In Fig. 5 I have illustrated one of said doors in an open position, while the other door is closed, the object of the doors being to afford means for introducing food and drink into the receptacles 10 and 11.

In Figs. 6, 7, and 8 I have illustrated another form of construction for my improved natural-hen incubator, wherein it will be observed 30 that the plurality of doors are vertically operated instead of being moved laterally, as shown in preceding views. The incubator proper is formed substantially the same as illustrated in Figs. 1 and 5, except that the 35 end sections 27 and the partitions 28 are preferably formed of a single piece of board, as illustrated in Fig. 4. The object in thus producing the end sections and partition-walls is to economize lumber in locations where this 40 commodity is scarce and expensive.

By reference to Fig. 4 it will be observed that one edge of the board may be so sawed or beveled as to produce the section 29, which latter may be in turn beveled at its extreme 45 corner to produce the point 30, which latter may be utilized in the manner set forth in said view.

It will of course be understood that I reserve the right to form these partitions and 50 end sections in any preferred way, though for the purpose of economy I have illustrated and described the plan as immediately set forth. Each of the partition-walls 3 is provided with a suitable opening 31, correspond- 55 ing to the opening formed by the offset 4 in Fig. 1, and in order to provide a convenient form of door or closure for this opening I have adopted the vertically-sliding door-sections 32, which are adapted to move in ver- 60 tical guideways formed by the cleats 33, located at a convenient point upon the partition-walls 28, and in order to provide reliably-efficient means for simultaneously opening these doors I form the anchoring-ear 34, at- 65 tached at a convenient point to the board section 35, which latter is secured to a con-

tiguous part of the partition-walls 28 and end sections 27. Pivotedly connected to the ears or brackets 34 is the bell-crank 36, operatively connected to the controlling-rod 37, 70 which latter extends entirely across the incubator-frame contiguous to all of the doors and in connection with the bell-crank thereof, said rod being operatively connected to the controlling-lever 38, pivotally mounted in 75 the bracket 39, attached at a convenient point to the end section 27. The other end of the bell-crank is pivotally connected to the link-section 40, the opposite end of the link being pivotally attached to the upper part of its respective door 32, and it is obvious that by an outward movement of the lever 38 the bell-crank 36 will be so manipulated as to cause the link 40 to elevate its respective door, while an inward movement of said lever will insure that all of the doors will be simultaneously depressed or disposed in a closed position. 85

In Fig. 8 I have shown the position of the bell-crank and coöperating parts when the 90 door is in an open position, while in Fig. 7 I have illustrated the relative arrangement of the parts when the doors are closed, it being clearly apparent that all of the doors may be instantly operated as desired, thereby ren- 95 dering it unnecessary for the attendant to separately open each individual door.

I prefer to connect the doors 6 to the side walls 2, as the inner edge of the door will thus rest upon the upper edge of the partition-walls 3, while the shaft 16 will rise above the edge of the door and prevent the latter from being casually blown open by the wind. It will be seen that my improved natural-hen incubator may be slightly increased in 105 width, and thereby double its capacity, without very materially increasing the cost, inasmuch as very little additional material is required for a double incubator over that necessary to produce the single form of incubator illustrated in Fig. 1.

While I have described the preferred construction and combination of the various parts deemed necessary in carrying out my invention, I reserve the right to make such 115 modifications and changes as I may find most desirable in practice and productive of the best results, and I do not, therefore, wish to be confined strictly to the exact showing herein presented, inasmuch as various substitutes 120 and equivalents may be adopted without departing from the scope and purview of my invention. It will also be understood that the proportions or size of the various parts illustrated may be modified or changed at 125 will and that any material may be employed deemed most suitable for the purpose. It is also clear that the capacity may be increased.

My improved natural-hen incubator will be found very desirable not only for the purpose 130 of protecting a sitting fowl during the process of incubation, but will in many instances

actually induce the fowl to sit when safely inclosed and housed against outside disturbing causes.

The various parts of my improved natural-
5 hen incubator may be very cheaply and expeditiously constructed even by a person who is not skilled in such work by following the constructions and plans hereinbefore set forth, and having thus fully described the construction and manner of using my improved incubator further reference to the details thereof is deemed unnecessary.

Having thus fully described my invention, what I claim as new, and desire to secure by
15 Letters Patent, is—

The herein-described hen-protector and brooder consisting of a main compartment having a plurality of individual nest-compartments, the wall of each nest-compartment being cut away at its upper corner, guides within said compartment; vertically-movable doors mounted to move in said guides; a fixed strip 35 adjacent to said compartments; ears

rising from said strip one for each door, a bell-crank lever pivotally mounted in each of 25 said ears, a reciprocating controlling-rod parallel with said strip and pivotally connected with the short arms of the bell-crank levers; inclined links pivotally connected at one end to the central upper portions of the doors and 30 their other ends pivotally connected with the long arms of the bell-crank levers, the pivots of the bell-crank levers, and the pivots of the links with the doors being upon opposite sides of the controlling-rod, and a controlling-lever 35 pivotally mounted near the base of the compartment having a longitudinally-disposed slot in which works a pin carried by the outer end of the controlling-rod, all substantially as herein shown and described.

In testimony whereof I affix my signature in presence of two witnesses.

JOHANN FRIEDRICH SIEMS.
